UNITED STATES PATENT OFFICE.

JAMES R. DUPEN, OF CHICO, CALIFORNIA.

WEATHER STOP.

Application filed October 24, 1927. Serial No. 228,400.

The invention relates to improvements in weather-stops of the type designed for mounting in a groove in the lower end of a door or other pivoted closure, provision being made for depressing the stop when the door or the like is closed and for retracting it when the closure is opened.

For purposes of description and convenience, the word "door" will be hereinafter used in a sense comprehending any other form of pivoted closure than an actual door, for instance, a casement window.

One object of the invention is to provide a new and improved casing construction for the depressible weather strip, provided with novel means for attaching it to the door.

A further aim is to provide unique operating means for automatically depressing the spring-raised weather-strip when the door is closed.

Yet another aim is to provide a unique thrust device for bringing the strip-depressing means into play when the door is closed, said thrust device being adjustable to permit proper initial setting of the device and to compensate for wear of the weather strip by contact with the sill.

With the foregoing in view, the invention resides in the novel subject matter herein-after described and claimed, the description being supplemented by the accompanying drawing.

Fig. 1 is a side elevation partly in section showing the invention applied to a door.

Fig. 2 is a longitudinal sectional view.

Figs. 3, 4 and 5 are horizontal sectional views on the correspondingly numbered lines of Fig. 2.

Figs. 6 and 7 are vertical transverse sectional views as indicated by lines 6—6 and 7—7 of Fig. 2.

In the drawing above briefly described, the numerals 8 denote two horizontally elongated sheet metal plates which are disposed in spaced vertical planes, the upper edges of said plates being provided with overlapped flanges 9 secured together by bolts or the like 10, while the ends of said plates are provided with inwardly stamped lugs 11 which are also disposed in overlapping relation. The innermost of these lugs have nuts 12 soldered thereto, and said lugs are apertured in line with the openings of the nuts. In this connection, it may also be stated that the nuts 13 of the bolts 10 are preferably soldered to the lowermost of the flanges 9.

Two vertically disposed end plates 14 are provided for the casing formed by the connected plates 8, said plates being of a length to project above the casing and being of a width to project laterally in opposite directions therefrom. These plates are provided with upper openings 15 to receive attaching fasteners 16 for securing them to the opposite edges of a door, said plates being inset in said edges, as shown. The plates 14 are also formed with lower openings 17 horizontally aligned with the nuts 12 and the openings of the lugs or ears 11. Screws 18 pass through the openings 17, through the openings of the lugs or ears 11 and are threaded into the nuts 12. Thus, the end plates 14 are effectively connected with the casing for supporting the latter in a groove 19 formed in the lower end of the door 20, and if the device be applied to a door of somewhat excess width, the screws 18 will permit the necessary outward spacing of the plates 14, from the ends of the casing.

A metal-backed weather strip 21 of felt or other desired material, is slidably mounted in the casing and its back 22 is suitably connected at 23 with a spring 24, the latter being securely mounted in the casing, with the aid of pins 25 and 26 whose ends are received in openings in the plates 8, said spring having an eye 27 through which the pin 25 passes, while the pin 26 merely underlies said spring. This spring acts in a manner to lift the weather strip when such lifting is permitted, but as long as the door stays closed, said strip is held in a depressed position in contact with the door sill, by means hereinafter described.

A bell crank 28 is fulcrumed in the casing and is provided with a relatively long horizontal arm 29 and a comparatively short vertical arm 30, the former being suitably related with a strip 21 while the arm 30 projects upwardly through a slot 32 formed in the top of the casing near one end of the latter, said casing top preferably having upstanding longitudinal flanges 33 along the edges of this slot.

Between this slot and the adjacent end of the casing, the casing top is provided with a pair of horizontally aligned plunger guides 34, and the adjacent end plate 15 is formed with an opening 35 aligned with said guides. A plunger 36 is slidable in the guides 34 and is formed with a reduced end 37 passing outwardly through the opening 35, while the inner end of this plunger is directed upward-

ly and inwardly at 38, extends through the slot 32 and contacts with the bell crank arm 30. Thus, inward pushing of the plunger 37, causes rocking of the bell crank 28 to depress the weather strip 29 against the action of the spring 24, but as soon as outward movement of said plunger is permitted, the spring will again raise the weather strip.

A novel thrust device is carried by one side of the door frame 39 for inwardly forcing the plunger 36 when the door is closed. This thrust device embodies a wood screw 40 having an enlarged head provided with an axial socket 41. A set screw 42 is threaded 15 adjustably into this socket and a lock nut 43 is provided for said set screw. The head of the screw 42 strikes the reduced end 37 of the plunger 36 to effect inward sliding of the latter when the door is closed but upon opening of said door, the plunger is released to permit raising of the strip 21 under the influence of the spring 24.

When initially applying the device, the screw 42 may be adjusted to the proper extent 25 and then locked by the nut 43, insuring that upon closing of the door, the strip 21 shall be depressed into tight contact with the door sill. Later on, if the lower edge of the strip 20 21 becomes so worn that it does not tightly contact with the sill, the screw 42 may be adjusted outwardly from the screw 40, causing it to inwardly force the plunger 36 to a greater extent, thus compensating for the wear.

35 As excellent results are obtainable from the details disclosed, they are preferably followed. However, within the scope of the invention as claimed, variations may be made.

I claim:—

40 1. In a weather stop, a horizontally elongated open-ended casing for reception in a groove in the lower end of a door, said casing having members in its open ends formed with openings, a pair of vertical end plates for said

casing of a length to project upwardly therefrom, said plates having lower openings alined with the aforesaid openings and upper openings above the casing to receive fasteners for securing the plates to the door edges, and threaded fasteners passing through said lower openings and the first named openings, said threaded fasteners permitting different spacing of the end plates from the casing to compensate for variance in door widths. 45

2. In a weather stop, two horizontally elongated plates disposed in spaced vertical planes, said plates having overlapping longitudinal flanges at their upper edges secured together, and overlapping ears at their ends formed with horizontally alined openings, 50 end plates for the casing of a length to project upwardly from said casing, said end plates having lower openings alined with the first named openings, and upper openings above the casing to receive fasteners for securing the plates to the edges of the door, and threaded fasteners passing through the lower openings and through said first named openings. 55

3. A weather stop comprising a horizontally elongated casing for mounting in a groove in the lower end of a door, the top of said casing being provided near one end with a slot and with plunger-guiding means between said slot and end, a spring-raised 70 weather strip in the casing, a bell crank fulcrumed in said casing and having a horizontal arm engaged with said strip and a vertical arm projecting upwardly through said slot, and an operating plunger for said bell 75 crank, said plunger being slidably mounted in said plunger-guiding means and having an upwardly and inwardly directed inner end which passes through said slot and abuts said vertical arm of the bell crank. 80

In testimony whereof I have hereunto affixed my signature.

JAMES R. DUPEN.
